UNITED STATES PATENT OFFICE.

HARRY H. BAER, OF ORRVILLE, OHIO.

VACUUM ORE-SEPARATOR.

1,186,874.

Specification of Letters Patent. Patented June 13, 1916.

Application filed January 18, 1916. Serial No. 72,706.

To all whom it may concern:

Be it known that I, HARRY H. BAER, a citizen of the United States, residing at Orrville, in the county of Wayne and State of Ohio, have invented a new and useful Vacuum Ore-Separator, of which the following is a specification.

My invention relates to improvements in vacuum ore separators, in which an open ended inclined, rotating cylinder is employed, said cylinder provided with agitating blades and vacuum creating means, whereby air is drawn from the open end of the cylinder, the partial vacuum formed being filled by the inrush of air at the bottom or lower end of the open ended cylinder.

Further the invention consists in providing an endless conveyer whereby the material designed to be treated is deposited intermediate the ends of the rotating cylinder.

The objects of the invention are, first, to remove by suction the lighter particles of metal producing ores or other metal carrying products, after the ore, rock or other metal carrying products have been reduced by a grinding process to a predetermined degree of fineness; second, to feed the ground product upon an endless conveyer whereby better distribution is brought about by extending the endless conveyer into the inclined rotating cylinder; and third to withdraw the air from the rotating cylinder while it is being rotated, the inclination of the cylinder being regulated or adjusted with reference to the material being treated. These objects, together with other objects readily apparent to those skilled in the art, may be attained by the construction illustrated in the accompanying drawings, although the invention may be embodied in other forms, the construction illustrated being chosen by way of example.

In the accompanying drawing: Figure 1 is a side elevation. Fig. 2 is an end view looking at the right hand end of Fig. 1. Fig. 3 is an enlarged view showing a portion of the cylinder, its driving ring and the bearing for said driving ring. Fig. 4 is a section on line 4-4, Fig. 5. Fig. 5 is a longitudinal section of the cylinder and a sectional view of the feed mechanism, the metal receiving spout and a portion of the vacuum chamber.

Similar numerals of reference indicate corresponding parts throughout the several figures of the drawings.

The frame of the machine to which the various parts are attached is made up of the end members or standards 1 and 2, said members being held the proper distance apart by means of suitable tie-bars 3 and 4, all of said bars constituting the frame being properly connected together to constitute a rigid structure. For the purpose of supporting the upper end of the cylinder 5, the bearing ring 6 is provided, which ring is connected to the downwardly inclined side 7, which downwardly inclined side 7 constitutes what might be termed the front of the vacuum chamber proper. The front or lower end of the cylinder 5 is supported by the bearing ring 8, which ring is securely connected to the pivoted side bars 9, said side bars being pivoted to the fixed bearing ring 6 or its equivalent.

Upon the shaft 10 is mounted the sprocket wheel 11. Above the shaft 10 is located the shaft 12, which shaft is driven by the belt 13 and the pulley 14, which pulley is mounted upon the shaft 12. For the purpose of imparting movement to the endless conveyer 15 which is extended into the cylinder 5, the shaft 16 is provided, which shaft is properly journaled in one of the pivoted bars 9. For the purpose of rotating the shaft 16, together with the different parts connected thereto, the sprocket wheel 17 is secured upon the shaft 16. For the purpose of imparting motion to the shaft 16 the sprocket chain 18 is provided, said sprocket chain also imparts rotary motion to the shaft 10, the driving wheel for the sprocket chain 18 being the sprocket wheel 19 mounted upon the shaft 12.

In order that the inclination of the cylinder 5 may be varied as hereinafter described provision must be made for holding the sprocket chain 18 in proper tension, regardless of the adjustment of the lower end of the cylinder 5 and in order to accomplish this result the drive chain 18 is located around the sprocket wheel 19 and extended down and around the sprocket wheel 20, thence upward and over the idler 21, which idler is journaled in the bracket 22, said bracket being secured to and adjustable with one of the pivoted bars 9, the drive chain is

extended around the sprocket wheel 17, thence under the sprocket wheel 11, and upon the sprocket wheel 19.

It will be understood that by journaling 5 the shaft 12 and the shaft 23 in bearings fixed to the frame proper the tension of the drive chain will not be changed by reason of the adjustment of the lower end of the cylinder up or down. It will be understood 10 that the adjustment of the lower end of the cylinder is comparatively slight, a few inches being sufficient to bring about the results desired. The endless conveyer 15 is located around the pulleys 24 and 25, the 15 pulley 24 being the driving pulley for the endless conveyer. The endless conveyer is inclosed in a suitable casing 26, which casing is held at the proper angle and in substantial alinement with the rotating cylinder 5, 20 by means of the shaft 10 and the cross bar or bolt 27.

For the purpose of conducting the material upon the conveyer 15 the casing 26 is provided with the feed tube 28, into which 25 feed tube is extended the funnel 29, which funnel is telescopically connected to the feed tube 28. The funnel 29 should be held in fixed relationship with reference to the frame which may be by the bar 30 or its 30 equivalent. Above the funnel 29 is located the feed roller 31, which feed roller is driven by the sprocket wheel 32 and the drive chain 33, said drive chain being driven by a sprocket wheel mounted upon the shaft 12. 35 Above the feed roll 31 is located the hopper 34, into which hopper the previously ground ore, rocks or other material is placed, the amount of the material fed on to the conveyer 15 being regulated by means of the 40 adjustable gate 35, which adjustable gate may be of any desired construction, as its only object is to regulate the quantity to be fed upon the endless conveyer.

The cylinder 5 is provided upon its inner 45 surface with radial agitating blades 36, which blades are formed of a length to correspond substantially with the length of the cylinder. It will be understood that as the cylinder is rotated the material fed into 50 the cylinder will be agitated, thereby mingling the material with the air as it passes through the open ended cylinder.

At the upper end of the cylinder and communicating therewith is located a separating 55 chamber or box 37 to which is attached the suction pipe 38, said suction pipe leading to and communicating with the suction fan 39, which suction fan is driven by the belt 40 or its equivalent. Within the 60 separating chamber is located the baffle plate 41, which is inclined downward and away from the cylinder and is located between the cylinder and the outlet end of the suction pipe 38. The baffle plate 65 41 is for the purpose of separating the air

from the refuse or lighter materials or non-metal portions of the ground ore or rock and directing such material to the inclined bottom of the separating chamber or box 37.

At the lower edge of the inclined bottom is 70 located the hinged door 42, said hinged door being automatically opened by the weight of the material or refuse coming against the door. For the purpose of normally holding the door closed a suitable spring 43 75 may be provided, but the construction of this spring is immaterial.

It will be understood that the suction of the air against the inner surface of the door holds the same closed until the weight of 80 the refuse overcomes the suction or overcomes the strength of the spring at which time the door is automatically opened and the refuse permitted to pass through the opening.

As above pointed out the rock or ore designed to be treated is first ground to the desired degree of fineness, but owing to different degrees of richness and different kinds of metal bearing ores, different degrees of inclination of the separating cylinder are necessary. Owing to the fact that some metals are heavier than others it is necessary to adjust the inclination of the cylinder so that the precious metals will 95 not be drawn upward, but move down the inclined cylinder and be deposited in a suitable receptacle or spout 44.

For the purpose of imparting rotary motion to the cylinder 5 the ring 45 is provided, 100 which ring is secured to the cylinder in any convenient and well known manner. Said ring is preferably L-shaped in cross section so as to provide suitable flanges, one of said flanges being for the purpose of providing 105 means for attaching the ring to the cylinder and the other flange being for the purpose of providing a contact surface for the driving wheel 46, the driving wheel 46 being securely mounted upon the shaft 16, which shaft is 110 driven by the sprocket chain 18 and the sprocket wheel 17. For the purpose of reducing the friction as between the bearing ring 8 and the driving ring 45 anti-friction rollers 47 should be provided, which anti-friction rollers are located so that the thrust 115 of the driving ring will come against the anti-friction rollers 47, said anti-friction rollers being journaled upon suitable bearings 48, which may be ordinary lug bolts. 120

For the purpose of adjusting the inclination of the cylinder and holding the same in proper adjustment, the screw threaded support or shaft 49 is provided, which shaft is held in suitable brackets 50. Upon the screw 125 threaded shaft 49 is located the adjusting wheel 51, said wheel being provided with a screw threaded opening through which the screw threaded shaft passes, by which arrangement rotating the wheel in one di- 130

rection will elevate the shaft and rotating it in the opposite direction will permit the shaft to move down. To the top or upper end of the shaft 49 is attached the head 52 which head forms a support for the cross bar 53, which cross bar is attached in any convenient and well known manner to the pivoted bars 9.

For the purpose of regulating the suction 10 of the fan 39 the shutter 54 shown in dotted lines Fig. 1 is provided, which shutter is adjusted by means of the screw threaded rod 55 and the wheel 56.

Having fully described my invention what 15 I claim as new and desire to secure by Letters Patent, is:

1. In a vacuum ore separator, the combination of a suitable frame, an inclined rotating open ended cylinder, said cylinder 20 provided upon its inner surface with agitating blades, an air pipe communicating with a suction fan, said suction fan adapted to draw air through the open ended cylinder, pivoted bars located upon opposite sides of 25 the cylinder, a bearing ring secured to said bars, said bearing ring adapted to support the lower end of the cylinder and an endless conveyer located in substantial alinement with the rotatable cylinder and means for 30 adjusting the inclination of the endless conveyer and cylinder.

2. In a vacuum ore separator, the combination of a frame, an adjustable inclined open ended cylinder, a chamber located at

the upper end of the open ended cylinder, a 35 suction fan and a pipe, said pipe and suction fan adapted to draw the air through the open ended cylinder, an endless conveyer extended into the open ended cylinder and means for rotating the cylinder and the 40 endless conveyer and means for adjusting the inclination of the endless conveyer and cylinder.

3. In a vacuum ore separator, the combination of a frame, an open ended cylinder, 45 bearing rings adapted to rotatably support the open ended cylinder, bars pivotally connected to the frame, one of the bearing rings for the cylinder connected to the pivoted bars, an endless conveyer extended into the 50 rotating cylinder and means for adjusting the inclination of the endless conveyer and cylinder in unison.

4. In a vacuum ore separator, the combination of a frame, an open ended cylinder 55 provided with agitating blades, bearing rings adapted to rotatably support the open ended cylinder, bars pivotally connected to the frame, one of the bearing rings for the cylinder connected to the pivoted bars, 60 an endless conveyer extended into the rotating cylinder and means for adjusting the inclination of the endless conveyer and cylinder in unison.

In testimony that I claim the above, I 65 have hereunto subscribed my name.

HARRY H. BAER.
